UNITED STATES PATENT OFFICE.

JOHN G. ROBERTS, OF DOBBS FERRY, NEW YORK, ASSIGNOR TO WESTERN ELECTRIC COMPANY, OF NEW YORK, N. Y., A CORPORATION OF ILLINOIS.

CURRENT-IMPULSE TRANSMITTER.

1,148,800.

Specification of Letters Patent.

Patented Aug. 3, 1915.

Application filed February 28, 1914. Serial No. 821,718.

To all whom it may concern:

Be it known that I, JOHN G. ROBERTS, a citizen of the United States, residing at Dobbs Ferry, in the county of Westchester and State of New York, have invented certain new and useful Improvements in Current-Impulse Transmitters, of which the following is a full, clear, concise, and exact description.

10 This invention relates to apparatus for transmitting signaling impulses suitable for the control of automatic switches of telephone exchanges. Its object is the selection and transmission of code impulses.

15 In accordance with this invention there is provided a single commutating device for sending the impulses and this device is capable of selective adjustment and operation preferably by manipulating a series of push 20 button plungers. The sending mechanism, may comprise switch contacts connected to a line and a source of current coöperating with a commutator cylinder having a plurality of insulating segments on its surface.

25 These insulating segments are divided into groups, any one of which is adapted to be selected, through various movements of the cylinder, to manipulate the switch contacts in a manner to transmit currents of electricity designed to make up a different combination or code of impulses for each group 30 of segments. The cylinder may be actuated through the agency of the series of plungers, any one of which when depressed, may set 35 a particular group of segments associated therewith in an operative relation to the switch contacts, and may also actuate a motor mechanism for the manipulation of the switch contacts.

40 Heretofore in automatic telephone systems, impulses varying in number from 1 to 10 for each character or digit have been employed to call a subscriber's number through suitable apparatus at central office.

45 This invention may be used in connection with a circuit closed to battery and leading to and connected with apparatus at central office, capable of registering and translating code impulses to call a subscriber, each digit 50 in a subscriber's number corresponding to a particular combination of such impulses, such a system being the subject of another

application of this applicant Serial No. 778,749, filed July 12, 1913.

In this particular form of the invention 55 two kinds of impulses are used; a full impulse produced by a full interruption of the circuit, and a partial impulse produced by a partial interruption of the circuit by means of the introduction into the circuit 60 of a resistance shunt coil. By varying the order of succession of these two kinds of impulses, a code of twelve characters may be produced with a maximum of three and a minimum of two impulses for each character. 65

The invention will be particularly described and the various features thereof explained in detail by reference to the accompanying drawings in which: 70

Figure 1 is a diagrammatic layout of the commutator and a simple circuit arrangement that may be used therewith; Fig. 2 is a cross-sectional view of the mechanism taken substantially on the line 2—2 of Fig. 75 4; Fig. 3 is a fragmentary elevation of the mechanism looking principally along the line 3—3 of Fig. 2; Fig. 4 is a fragmentary plan view of the mechanism taken of the line 4—4 of Fig. 2; Fig. 5 is a plan view 80 of the mechanism shown in Fig. 3; Fig. 6 is a perspective view of a plunger locking plate and commutator brushes; Fig. 7 is a perspective view of one plunger and its associate parts; Fig. 8 is the bottom view of 85 the shaft-actuating pawl and ratchet taken on the line 8—8 of Fig. 3.

The same letters of reference are used to designate the same parts wherever they are shown. 90

Referring to the diagram, Fig. 1, to illustrate more clearly the mechanical principles on which the invention is based, the surface of a commutator 11 is shown laid out flat and the separate insulating segments 12 95 thereon placed in their relative position. The commutator 11 is adapted by the depression of series of buttons to move, first, downward, second, a varying angular distance, third, upward and finally a continued 100 angular distance so that when returned to normal position it has made a complete revolution. The stationary brushes or switch contacts 13, 14 and 15 therefore contact with

the surface at the normal position marked N on the commutator when it is moved downward, and later when moved upward they contact at a position corresponding to the particular button selected. It is this upward movement that causes the connection between the brushes to be variously interrupted by insulating segments, and there are twelve positions marked from 0 to 9 and 10 X and Y that may be placed in such operating relations to the brushes.

To impart these various movements to the commutator, I have provided a mechanism which may be operated by a series of plungers 16 arranged in a circular row and having buttons 17 with characters inscribed thereon so as to correspond with the figures on the face of the watch. A finger guide plate 18 is provided to guide the operator's 20 finger on the particular button depressed so that the adjacent buttons may not be accidentally displaced during this operation.

Referring now more especially to Figs. 2 and 7, it may readily be seen that any one 25 of these plungers when depressed moves a lever 19 downward, but is prevented from operating this lever a second time after having once returned upwardly the smallest distance. This is done by means of a spring 20 having an angular projection 21 that slips 30 in under the lever-actuating pawl 22 during the depression of the plunger and which therefore throws the pawl out of engagement at notch 23 the moment the plunger 35 starts to return upward. The pawl cannot again be placed in operative position until both the lever 19 and the plunger 16 have fully returned to normal, when the wedge 24 integral with the top supporting plate 25, 40 forces the projection 21 from under the pawl which then again engages the notch 23 under pressure of spring 26.

Any one of the levers 19 when thus operated forces the circular locking plate 27 45 downwardly and is locked therewith, by means of an angular extension 28 and catch 29 at the free end of the lever which move into an aperture 30 in the plate, and by means of a slight angular movement given 50 to the plate at this time. Integral with the plate is a downwardly extending arm 31 having its lower portion slightly offset and straddled by two fixed guide members 32 and 33. This offset portion will, therefore, 55 when the plate moves, be guided to impart to the plate the angular movement mentioned above, and the direction of which is shown by the arrow point in Fig. 6.

The body portion 34 of the commutator 11 60 is mounted on the shaft 35 so that it will rotate therewith, but will have an independent vertical movement thereon, and is for that purpose keyed to the shaft by means of a projection 36 on the body-portion engaging the longitudinal slot 37 in the shaft.

The upper portion 38 of the commutator is rotatably mounted in the hub 39 of the locking plate and held in place by means of a nut 40, and must therefore participate in the vertical movement of the plate but may rotate independently thereof.

Referring now particularly to Fig. 6 wherein is shown two resting plates 41 and 42 for the commutator brushes 13, 14 and 15. The normal resting plate 41 is the segmental piece shown attached to but insulated from the U-shaped projection 43 extending from the lower offset portion of arm 31. The off-normal resting plate 42 is the segmental piece shown attached to but insulated from the projection 44 integral with plate 27 and extending downwardly therefrom. The brushes 13, 14 and 15 are attached to but insulated from the supporting member 45 which in turn is rigidly secured to the frame 80 member 46. This member 45 is integral with guide members 32 and 33 as well as with the normal stop projection 47 for commutator 11. This stop 47 has an insulating end-piece 48 that engages a rib 49 attached to the periphery of commutator 11. This rib serves to hold the commutator against rotation during its journey downward and to prevent it from making more than one complete revolution for each operation of the mechanism.

To impart to the commutator after it has been moved downward by the depression of a plunger a varying rotary motion, then slowly return it upward and again rotate it 100 so that it has made a complete revolution, there is provided a winding and controlling mechanism which is best illustrated in Figs. 2, 3, 5 and 8, and is as follows: The commutator has a circular rack extension 50 adapted to rotate the pinion 51 and the double acting locking pawl 52, the latter being permanently fixed to the former in an angular relation by means of an arm 53 and a shaft 54. This locking pawl 52 engages a notch 55 in a 110 disk 56 when moved by the rack in a clockwise direction, but will, after having traveled 180 degrees in that direction, be rendered inoperative, with regard to the transmission of any further movement to the 115 disk, by engagement with a fixed pin 57 which disengages it from the notch 55. Integral with disk 56 is a gear-wheel 58 meshing with a pinion 59. This pinion is adapted to rotate a pair of bevel gears 60 and 61 120 by being mounted integral with gear 60 on the shaft 62 supported in frame 46.

The beveled gear 61 mounted loosely on shaft 35 is provided with a hub to which the inner end of a spiral spring 63 is attached. 125 The other end of this spring is affixed to the frame 46 so that when the beveled gear is rotated it will store up power in the spring. Disk 64, which is permanently affixed to the hub of the beveled gear 61, carries a spring 130

pressed pawl 65 adapted to engage the one-toothed ratchet wheel 66 affixed to shaft 35 for the purpose of transmitting said stored up power in spring 63 to the shaft 35 whenever free to rotate.

The upward movement of commutator 11, which is under tension of spring 67, is retarded by means of a governor mechanism consisting principally of a disk 68 integral with gear wheel 69 which meshes with the pinion 70. This pinion is integral with the worm wheel 71 engaging a worm 72 that operates the governor 73 having the usual weighted springs 74 and friction drum 75. The pawl 52 is adapted when thrown out of control of the winding mechanism to immediately engage the notch 76 (shown in full lines in Fig. 2) in disk 68 and thereby be coupled to the escapement mechanism to retard the upward movement of the commutator.

The plunger and lever mechanism is supported and carried by the top supporting plate 25 and its downwardly extending projections 77, as well as by a tubular shell 78 having ears 79 punched in from its sides to form a seat for the plunger actuating springs 80. The shaft 35 is supported between the top plate 25 and the bottom plate 81, the latter serving also as a seat for the frame 46 that carries the winding mechanism, commutator brushes and other parts as shown and for the governing mechanism. The top and bottom plates are held together by the shell 78 which is secured to both these plates by means of screws. The whole structure is enclosed in dust-proof shell 82.

The operation of the mechanism is briefly as follows: When the commutator is moved downward by the depression of a plunger, the commutator rack 50 rotates the pinion 51, locking pawl 52, disk 56 and gear 58, an angular distance of 180 degrees in a clockwise direction. This rotation of gear 58 is sufficient to impart to gear 61 and disk 64 a complete revolution, by the proper multiplication of movement in gears 59, 60 and 61, and winds the spring 63. The shaft 35 is therefore put under tension of spring 63 by reason of the pawl 65 on disk 64 having rotated a complete revolution and allowed to engage the single tooth on wheel 66. The spring 63 is now free to rotate shaft 35, because pawl 52 has been tripped by pin 57 and disengaged the disk 56 and associated gearing. The rotary moving power transmitted through shaft 35 to the commutator is, however, not immediately used up, but the commutator is stopped in its rotation at some point or other of its journey. This is accomplished by means of a stop 83 on the upper surface of the commutator 11 engaging the latch 29 of the particular lever 19 depressed, and being held thereby until said commutator has had time to return upward,

at which time the lever is released, allowing the commutator to resume its rotary journey back to normal. Before the commutator starts to return upward the pawl 52, by means of the rocking movement it receives when disengaged from the disk 56, engages the notch 76 in the disk 68 of the speed-governing mechanism, and the return journey of the commutator is thereby retarded. The speed-governing mechanism is immediately released as soon as the commutator has returned to normal, as the pawl 52 is disengaged by the fixed pin 34 from the disk 68. The pawl 52 is thereby rocked to again engage a notch 55 in disk 56 in readiness to control the winding mechanism when actuated by the depression of another plunger.

Referring again to the diagram in Fig. 1, it may be assumed, for example, that it is desired to transmit a combination of one full, followed by one partial, followed by one full impulse over the line wires to the central office. This combination may represent the character 6, and may be recorded, registered and translated through suitable automatic selecting mechanisms at the central office to connect with the subscriber's line No. 6 and the following sequence of operations would then take place. First, the calling subscriber lifts his receiver off the hook 85 to call, establishes a closed circuit for the grounded battery 86 at the central office, a current flowing then from battery 86 to relays 87 and 88, line wire 89, switch contacts 13, 14 and 15, wire 90, substation apparatus, switch-hook contact 91, line wire 92, relay 93, and back to battery 86 and ground. Second, the commutator and resting plates 41, 42 are caused to move downwardly until the switch contacts rest on the plate 42. This movement has no effect on the current in the line as a closed circuit is continually provided between the contacts across these parts. Third, the commutator now revolves until the portion designated 6 takes the position formerly occupied by the portion N between the plates 41 and 42. Fourth, the commutator and resting plates are then caused to return upward to their normally elevated position, and while doing so the current is momentarily disturbed between the contacts in three successive steps: first, by the contacts 14 and 15 being traversed by insulating segments 94, thereby causing a full interruption; second, by the contact 14 being traversed by a similar segment 95, thereby causing a partial interruption by leaving the resistance coil 96 in the line; and third, by the contact 13 being traversed by the insulating segment 97, causing a second full interruption. In a similar manner any other combination of full and partial impulses may be sent out on the line, to represent the other characters designated as shown, by merely varying the angular

movement of the commutator and thereby placing any other portion thereof, having different combinations of insulating segments, in a position to combine the contacts 5 in different sequence of operations.

When the calling subscriber closes his circuit at switchhook contact 91, all three relays 87, 88 and 93 are operated. A full interruption has no effect on relay 93 which is 10 made slow acting, but deenergizes relays 87 and 88. A partial interruption has no effect on relays 93 and 87, the latter being what is known as a slow-release relay. Relay 88, however, will let its armature fall back, as it 15 is made to operate only on a full current potential. By this arrangement of preliminary recording relays at central office, the different current combinations set up at the substation can be made to operate 20 other automatic selecting devices associated with said relays to effect communication between the calling and the called subscriber.

What is claimed is:

1. In a code impulse transmitting device, 25 a plurality of fixed contacts, a commutator having thereon a plurality of contacts arranged in groups, a plurality of plungers, a lever associated with each of said plungers, means actuated by any one of said levers 30 for selectively operating said commutator to position a group of contacts corresponding to the lever actuated in operative relation to the fixed contacts, and means storing energy from said lever when operated to restore said 35 commutator to normal, whereby the proper group of contacts thereon will engage said fixed contacts.

2. In a code impulse transmitting device, a plurality of fixed contacts, a commutator 40 having thereon a plurality of contacts arranged in groups, a plurality of plungers, a lever associated with each of said plungers, means actuated by any one of said levers for selectively operating said commutator to position a group of contacts corresponding to the lever actuated in operative relation to the fixed contacts, a locking means on each 45 of said levers adapted to engage the corresponding plunger during the actuating stroke thereof, a releasing means adapted to disengage said locking means from the plunger during the return stroke thereof to permit the return of the plunger and lever to normal independently of each other, and 55 means storing energy from the lever to restore said commutator to normal, whereby the proper group of contacts thereon will engage said fixed contacts.

3. In a code impulse transmitting device 60 a plurality of fixed contacts, a commutator having thereon a plurality of contacts arranged in groups, a plurality of plungers, a lever associated with each of said contacts, means actuated by any one of said levers for 65 operating said commutator, an extension on

said levers and a projection on the commutator adapted to position a group of contacts corresponding to the lever actuated in operative relation to the fixed contacts, a locking means on each of said levers adapted to 70 engage a corresponding plunger during the actuating stroke thereof, a releasing means adapted to disengage said locking means from the plunger during the return stroke thereof to permit the return of the plunger 75 to normal independently of the lever, means associated with said commutator adapted to lock any one of said levers when actuated to said commutator for maintaining the operative relation of the contacts selected 80 on the commutator to the fixed contacts until the return thereof to normal position, and means storing energy from the lever to restore the commutator to normal, whereby the proper group of contacts thereon will 85 engage said fixed contacts.

4. In a code impulse transmitting device, a plurality of fixed contacts, a commutator having thereon a plurality of contacts arranged in groups, means for selectively operating said commutator with respect to the fixed contacts to position any combination of groups of contacts in operative relation thereto, means for moving said commutator past the fixed contacts, whereby a series of 90 impulses are sent varying in number and means connected to one of said fixed contacts for varying the degree of strength of any or all impulses of the combination selected. 95

5. In a code impulse transmitting device, a plurality of fixed contacts, a commutator having thereon a plurality of contacts arranged in groups, a plurality of plungers, means operated by each plunger for moving 100 said commutator longitudinally and rotatably into a position such that a group of contacts thereon corresponding to the plunger actuated will be opposite said fixed contacts, and means storing energy from said plungers for restoring said commutator to normal position partially by a longitudinal movement, whereby the proper group of contacts thereon will engage said fixed contacts and then by a rotary movement. 110

6. In a code impulse transmitting device, a plurality of fixed contacts, a commutator having thereon a plurality of contacts arranged in groups, a plurality of plungers, a lever associated with each of said plungers 120 for moving said commutator longitudinally, means responsive to such longitudinal movement of the commutator for the rotation thereof, means for detaining the commutator into position such that a group of contacts corresponding to the lever actuated will be opposite said fixed contacts, means responsive to the said longitudinal movement of the commutator for restoring said commutator longitudinally, whereby the proper 125 contacts 130

group of contacts thereon will engage said fixed contacts and means effective at the end of the return of the commutator longitudinally for releasing said commutator from the selected position allowing it to rotate back to normal position.

5 In witness whereof, I hereunto subscribe

my name this 26th day of February A. D., 1914.

JOHN G. ROBERTS.
